CLAIM

The ornamental design for a ladder inclinometer, as shown and described.

DESCRIPTION

FIG. 1 is a somewhat isometric view of a ladder inclinometer, showing my new design,
FIG. 2 is a view in front elevation,
FIG. 3 is a view in rear elevation;
FIG. 4 is a side view thereof;
FIG. 5 is a plan view thereof; and,
FIG. 6 is a bottom plan view thereof.

The flat interior surfaces of both levels, as well as the area above the curved level, are shaded to indicate contrast.
